UNITED STATES PATENT OFFICE.

CHARLES E. WAREAM AND GEORGE N. LINK, OF CINCINNATI, OHIO, ASSIGNEES, BY
DIRECT AND MESNE ASSIGNMENTS, OF ONE-HALF TO THE AMERICAN LAUNDRY
MACHINERY COMPANY, OF NORWOOD, OHIO, A CORPORATION OF OHIO, AND ONE-
HALF TO UNITED STATES HOFFMAN MACHINERY CORPORATION, A CORPORA-
TION OF DELAWARE.

POWER PRESSING MACHINE.

Application filed May 16, 1919. Serial No. 297,467.

This invention relates to garment pressing machines or, more generally, to machines for pressing woven fabrics or for ironing articles of wearing apparel. The invention 5 more particularly relates to that class of pressing machines embodying two co-operating relatively movable pressing members between which the work is pressed by pressure of the pressing members toward each other. 10 Such presses are usually operated by hand or foot operated treadles or levers connected by suitable mechanism to the movable pressing members. The degree of pressure secured in such a machine is, of course, limited 15 by the strength of the operator and the multiplication of power possible through the arrangement of connecting levers.

The present invention has for its object 20 to provide an improved pressing machine embodying a power attachment for securing heavy or increased pressure between the pressing members when desired, and more particularly a power attachment actuated by fluid pressure and co-operatively related 25 to the operating treadle or lever or other part of the operating mechanism for the movable pressing members.

A further object of the invention is to 30 provide a power attachment co-operatively related to the actuating treadle of the machine and in connection therewith means for insuring closing of the press or locking of said treadle in its depressed position before it is possible to manipulate the controller 35 to render the power actuating means effective, so as to prevent application of power before the treadle is locked and avoid any possibility of the pressure treadle flying up and injuring the operator or any other possible 40 damage to the machine or mechanism, thereby safe-guarding both the machine and the operator.

A further object of the invention is to 45 provide a fluid pressure power attachment for garment presses which can be controlled from a position at or near the pressing members, and which is also co-operatively related to the actuating treadle of the machine for automatic control thereby.

50 Further objects of the invention are in

part obvious and in part will appear more in detail hereinafter.

The invention comprises the construction and arrangement of parts hereinafter described and claimed.

55 In the drawings, which represent one suitable embodiment of the invention, Fig. 1 is a side elevation showing the press closed; Fig. 2 is a detail sectional view of the control valve mechanism, the section being taken 60 on the line 2—2, Fig. 5, looking in the direction of the arrows; Fig. 3 is a sectional plan view on the line 3—3, Fig. 1; Fig. 4 is a front elevation of the lower portion of 65 the machine, the foot plate of the pressure treadle being omitted for clearness of illustration; Fig. 5 is a sectional elevation on the line 5—5, Fig. 1; Fig. 6 is a sectional elevation on approximately the line 6—6, Fig. 4; Fig. 7 is a detail sectional view of 70 a controlling device; Fig. 8 is a detail view partly in elevation and partly in section on the line 2—2, Fig. 5; and Fig. 9 is a detail section on the line 9—9, Fig. 8.

75 The machine shown in the drawings comprises a suitable frame having a base 1 resting upon a suitable support and provided with front and rear columns 2 and 3 and a rearward lower extension 4. The front column supports the stationary lower pressing member 5 which may be padded, as is usual, and which may also have self-adjusting turning movement about a horizontal axis 6, to accommodate itself to the descending upper pressing member, as is customary 80 in machines of this class. The rear column 3 supports an arm 7 swinging about the horizontal axis 8 and provided at its front end with the co-operating upper pressing member or head 9 to which are attached 85 brackets 10. The rear end of said arm is provided with a counter-weight 11 and may be connected by the tension spring or springs 12 to a stationary support. The counter-weight and springs tend to open the press 90 and its closing movement is produced by the operating mechanism to be described.

95 13 indicates the actuating treadle provided with the usual foot plate 14, said treadle being pivoted near the back of the machine 100

at the point 15 in a manner presently to be described. This treadle is provided with an anti-friction member, such as a roller 16 which works across a cam surface 17 on one 5 arm 18 of a lever pivoted at 19 in the stationary frame, the other arm 20 of said lever having an anti-friction member such as a roller 21 which travels in front of and along a cam surface 22 on a downwardly 10 extending portion 23 of the arm 7. In the open position of the press the rollers 16 and 21 lie at the upper ends of their respective cam surfaces 17 and 22. When the treadle 13 is depressed, roller 16 travels 15 down along the cam surface 17, thereby turning lever 18, 20 in the counter-clockwise direction, Fig. 1, and causing its roller 21 to travel downwardly along the cam surface 22 and thereby move the head 9 downwardly into pressing relation with the bed 5. Arm 20 may be provided with an extension 24 having a roller 25 traveling behind and along a second cam 26 on the depending arm portion 23, which ties the arms 20 and 23 20 together and prevents lost motion therebetween.

Suitable mechanism is provided for locking the press in closed position. The mechanism shown comprises a locking hook 27 30 pivoted upon an arm 28 extending laterally from one side of the main treadle and having a hooked lower end portion 29 adapted when the press is closed to swing beneath a stationary shoulder or abutment 30 of the main 35 frame, as shown in Fig. 4, and thereby prevent upward movement of the operating treadle and the mechanism connected thereto. To release the lock the press is provided with suitable bearings for a cross shaft 40 31 to one end of which is connected a release treadle 32, and to which shaft is also connected an arm 33 having a portion lying beneath a projection 34 extending laterally from the locking member 27. 31^a represents 45 a counterweight for the release treadle.

The power attachment for the present machine comprises a fluid pressure cylinder which actuates a piston connected to a part of the operating mechanism for the movable 50 head, and more particularly the main actuating treadle. As illustrated the pressure cylinder 35 is mounted upon a bracket 36 supported by the rear extension 4 of the main frame. In said cylinder is a piston 37 55 whose rod 38 is rigidly connected to a cross head 39 having sleeve portions 39^a slidable upon stationary guide rods 41 carried by the bracket 36. To the cross head 39 is pivotally connected the rear end of the treadle 13 60 by the pivot pin 15 before referred to. When the treadle is fully depressed and locked as before described it lies substantially in a straight line coincident with the axis of the piston rod 38, as shown in Fig. 6. 65 Consequently movement of the piston 37 to

the right in Fig. 6 advances the treadle 13 and produces additional pressure of the anti-friction roller 16 against the arm 18 of the intermediate lever, the power pressure thus produced being transmitted through 70 such lever to the arm 27 and thence to the movable head, but such movement is not sufficient to disturb the locking effect.

Flow of pressure to and from the power cylinder is controlled by suitable valve mechanism including a hollow valve casing 40 attached to one side of the bracket 36. Said valve casing is provided with an inlet chamber 40^a communicating with the pressure supply pipe 42 connected to any suitable 80 source of fluid pressure, such as steam, compressed air, or the like, a pressure chamber 43 communicating through the pipe 44 with the chamber 45 of the pressure cylinder behind its piston 37, and an outlet chamber 46 communicating through the pipe 47 with an exhaust to the open air or to a condensing chamber, (not shown) as desired, 42^a represents a suitable valve for controlling the supply of fluid pressure to the inlet chamber. Between the chambers 40^a and 43 is a port 48 surrounding which is a valve seat for the controlling valve 49 lying in the inlet chamber 40^a and normally held to its seat by a compression spring 50, said valve 90 being provided with a stem 51 sliding through a packing 52 and pivotally connected at its upper end to one arm 53 of a lever pivoted at 54 to a stationary part of the frame. Communication between the chambers 43 and 46 is through a port 55 controlled by a valve 56 in the chamber 43 held downwardly to its seat by the pressure spring 57 and the upper end of whose stem is pivotally connected to a second arm 58 100 of the lever before referred to. Said lever has a downwardly extending arm 59 provided with a bifurcated lower end pivotally connected to a collar 60 slidable upon a rod 61 between two compression springs 62 surrounding said rod, and each of which springs at its opposite end bears against a collar 63 adjustably secured in suitable position on said rod by the set screw 64. Rod 61 is pivotally connected to a depending arm 110 of a three armed lever 65, one of whose arms is connected by a link 66 to a bell crank lever 67 pivoted on the frame, the opposite arm of said lever being connected to a sleeve 68 sliding on a rod 69 and lying in front 120 of a collar 70 adjustably secured thereon by the set screw 71. Rod 69 is pivotally connected at its front end to an arm 72 on a shaft 73 turning in the brackets 10, said shaft being provided with an operating handle 74.

Another arm of lever 65 is connected by a link 75 with a lever 76 pivoted at 77 to the stationary frame, said lever having a horizontal portion lying above an anti-fric- 130

tion member such as a roller 78 on an arm 79 connected to the release treadle shaft 31. The first named arm of the lever 65 to which the link 61 is connected has pivotally connected thereto a plunger 80 working in an opening in the side of a hollow casing 81 through which slides a vertically extending rod 82 having a horizontal opening 83 therein. Hollow casing 81 is rigidly supported on the side of the frame and beneath the same is a compression spring 84 surrounding rod 82 and lying above a collar 85 adjustably secured to the rod 82 by the set screw 86. Rod 82 at its lower end is pivotally connected to one arm of a lever 87 pivoted at 88 to the stationary frame and having a front arm 89 lying beneath an extended portion of the arm 28 carried by the treadle 13 and which supports the locking member 27, as shown in Figs. 1 and 4.

The operation is as follows:

The ordinary operation has already been described. To briefly repeat, depressing the foot treadle 13 swings the head downwardly against the bed until the press is locked by the locking member 27. It may be released at any time by depression of the release treadle 32. The press can be used in this way for certain classes of work without resort to the power mechanism and said power mechanism interferes in no way with such usual operation of the press.

If, however, a certain class of work demands heavy pressure the power attachment is utilized. When the treadle is locked in its lower position, as before referred to, the opening 83 in the slide rod 82 lies opposite the plunger 80. In this position, and in no other position, the controlling mechanism for the power attachment can be actuated, because in all other positions a blank portion of the slide rod 82 lies opposite the plunger 80 and prevents motion of the lever 65 in the clockwise direction, Fig. 1. Let us assume then that the press has been closed and locked by actuating treadle 13. In this position valve 49 is closed and valve 56 is open, as shown in Fig. 2. Chamber 45 of the pressure cylinder therefore communicates through pipe 44, chamber 43, and chamber 46 with the exhaust. By depressing handle 74 the collar 70 is advanced against the sleeve 68 and turns the lever 65 in the clockwise direction, Fig. 1. Valve 49 is held to its seat by the pressure in the inlet chamber 40^a. However, as the operating handle is depressed the spring 62 at the right in Fig. 1 is compressed until finally its pressure exceeds the pressure in chamber 40^a, whereupon lever arm 59 is suddenly moved to the left in Fig. 1, thereby opening valve 49 and at the same time closing valve 56. Pressure flows from chamber 40^a into the cylinder and moves the piston to the right in Fig. 6, thereby applying additional heavy pressure

to the pressing members. The valves remain in the new position until the fluid pressure is released, which is accomplished by actuating the release treadle 32. The first portion of the downward motion of treadle 32 elevates lever 76, which first compresses the left hand spring 62 in Fig. 1, and then suddenly shifts the valves to their original position, thereby cutting off the supply of fluid pressure to the chamber 45 and simultaneously connecting said chamber to the exhaust. Springs 90 surrounding the guide rods 41 and effective upon the cross head 39 thereupon retract the piston and treadle to their original positions. The second portion of the downward motion of the release treadle brings the lever arm 33 into co-operative relation with the extension 34 of the treadle lock and turns said lock, thereby unlocking the machine and allowing the head to rise from the bed as is usual.

The apparatus described not only permits heavy fluid pressure to be applied to the pressing members but also prevents movement or manipulation of the controlling means for the power mechanism in a manner to cause application of power pressure until the press is closed and, indeed, is locked, so that there is no danger of the application of pressure either causing the treadle 13 to fly up and injure the operator or in any other manner causing injury or damage either to the operator or any part of the mechanism. The machine is therefore amply safeguarded but, nevertheless, is capable of use either as a man press wherein the working pressure is entirely operator produced, or as a power press, wherein a power effect is secured, neither method of operation in any manner interfering with the other. Obviously the press is also safeguarded against undesirable or dangerously premature production of power pressure, because the controller or controlling means for producing power pressure cannot be moved, manipulated or operated unless the head is so close to the bed that the operator's fingers or arm could not possibly be between the head and bed or, at least, her fingers or arm would be slightly burned as a warning to remove them before applying power pressure.

What we claim is:

1. A pressing machine, comprising cooperating relatively movable pressing members, an operator operated device and connections therefrom to one of said members for producing closing movement thereof, power mechanism having operative connection with said member, a controlling device for said power means, release means, and means operated thereby for additionally controlling said power means and for also restoring said controlling device to normal position.

2. A pressing machine, comprising a stationary garment support, a cooperating mov-

able pressing head, operator operated means for closing the head upon the support, power mechanism having connections effective upon said head to secure pressure additional to that produced by the operator, controlling means for said power mechanism, means for locking the press closed, and operator operated release means operatively connected to said locking means and to said controlling means to move the locking means to release position and the operator operated part of said controlling means to initial position upon operation of said release means.

3. A pressing machine, comprising a stationary garment support, a cooperating pressing head adapted to be closed upon the work by the operator, power mechanism also

effective upon said head to produce final pressure additional to that produced by the operator, controlling means for said power means operable by the operator independently of head movement, means for locking the press closed, operator operated release means, and connections between said release means, locking means, and controlling means, whereby upon operation of said release means the press is opened and the operator operated part of said controlling means is restored to initial position. 20 25

In testimony whereof we affix our signatures.
